UNITED STATES PATENT OFFICE

WILLIAM C. EMBURY, OF ROCHESTER, NEW YORK, ASSIGNOR TO EMBURY MANUFACTURING COMPANY, OF ROCHESTER, NEW YORK, A CORPORATION OF NEW YORK.

LANTERN-GLOBE LIFTER.

992,411.

Specification of Letters Patent. Patented May 16, 1911.

Application filed January 5, 1911. Serial No. 601,022.

To all whom it may concern:

Be it known that I, WILLIAM C. EMBURY, a citizen of the United States, and resident of Rochester, in the county of Monroe and State of New York, have invented certain new and useful Improvements in Lantern-Globe Lifters, of which the following is a specification.

This invention relates to globe lifters, such as are used in connection with tubular lanterns of ordinary form, of the type in which a cranked lifter-shaft provided with a finger-lever is pivotally connected with the globe-plate of the lantern and is journaled on, or adjacent to, the side-tubes of the lantern.

The invention relates particularly to the member constituting a bearing and a detent for the lifter-shaft, and the object of the invention is to produce a device of this kind, capable of being formed of a single piece of sheet-metal, which shall be simple and rigid in structure and neat in appearance.

To this end the invention consists in a globe-lifter having the combined catch-plate and bearing hereinafter described, as it is defined in the succeeding claim.

In the drawings:—Figure 1 is a front-elevation of the lower portion of a tubular lantern provided with the present invention; Fig. 2 is a front perspective view of a portion of the globe-lifter, including the combined catch-plate and bearing; and Fig. 3 is a perspective view of the same parts from the rear.

The invention is illustrated as employed in connection with a tubular lantern of ordinary form, and in Fig. 1 portions of the lantern are illustrated, including the oil-font 4, the burner 5, the globe 6 and the side-tubes 7 and 8. The figure also illustrates a cranked lifter-shaft 9 constructed of resilient wire and of the ordinary form, which is attached to the globe-plate 10 by the usual pivotal connections (not shown). The lifter-shaft 9 is provided at its right-hand end with the usual upwardly-bent finger-lever 11 which is arranged to lie between the side-tube 8 and the globe.

The present invention resides particularly in the form of the combined catch-plate, bearing and bearing-support for the shaft 9. This device comprises a vertical

plate 12 which is perforated to receive the shaft 9. As shown in Fig. 3, the plate 12 is slotted inwardly from its edge to the perforation, thereby producing a tongue 13 which may be bent aside to admit the shaft and afterward bent back to close the bearing. The bearing-plate 12 is formed integral with a vertical side-plate 14 which connects one lateral edge of the bearing-plate with the side-tube 8 of the lantern. The side-plate 14 is preferably secured to the tube by soldering. A third portion of the bearing-support consists in a bottom-plate 15 which extends inwardly from the lower edge of the bearing-plate to the side-tube and is soldered to the tube. The bottom-plate 15 is also preferably integral with the bearing-plate and is joined to the lower edge of the side-plate 14. The joint 16 between the plates 14 and 15 may be formed either by stamping these parts from a continuous piece of sheet-metal, or by uniting their edges by means of solder.

The catch-plate consists in an upward extension 17 from the side-plate 14. This catch-plate has, at its lower extremity, a shoulder 18 beneath which the finger-lever 11 is retained when it has been depressed by the operator to raise the lantern-globe. Above the shoulder 18 the catch-plate has a long inclined cam-surface 19 over which the finger-lever rides easily while being depressed. The lifter-shaft 9 is resilient, and the finger-lever presses outwardly against the catch-plate, so that it is retained below the shoulder 18 until the finger-lever is pressed inwardly by the operator to release it. In the normal position of the parts the finger-lever is also retained in raised position by its engagement with the upper end of the catch-plate.

The arrangement, at right angles, of the side-plate 14 and the bottom-plate 15 by which the bearing-plate is supported produces a very rigid structure in which vertical strains are resisted effectively by the side-plate 14, while horizontal strains are resisted by the bottom-plate 15, since these plates lie with their greatest dimensions in these two respective directions. The box-like form produced by the plates 12, 14 and 15 also conduces to the substantial and ornamental appearance of the device, while at the same time the device can be con-

structed by a minimum number of operations, and can be readily and firmly secured to the side-tube by means of solder alone.

I claim:-

- 5 In combination with a tubular lantern, a globe, a globe-lifter comprising a cranked lifter-shaft connected with the globe-plate of the lantern and provided with a finger-lever located between the globe and one of
10 the side-tubes of the lantern, and a combined bearing and catch-plate for the lifter-shaft comprising a vertical bearing-plate located between the globe and the finger-lever and perforated to receive the lifter-

shaft, a bottom-plate connecting the lower 15 edge of the bearing-plate with the tube, a vertical side-plate arranged at a right angle with the bottom-plate and connecting a lateral edge of the bearing-plate with the tube, and a catch-plate above the side-plate 20 and lying against the tube, the catch-plate having an edge projecting inwardly toward the bearing-plate and provided with a cam-surface engaged by the finger-lever.

WILLIAM C. EMBURY.
